TABLE LAMP

Jacob A. Mehr, Kirkwood, Mo., assignor to Dazor Manufacturing Corp., St. Louis, Mo., a corporation of Delaware

Application November 10, 1958, Serial No. 53,320

Term of patent 14 years

(Cl. D48—20)

FIG. 1.

FIG. 2.

Fig. 1 is a top plan view of a table lamp embodying my new design; and

Fig. 2 is a perspective view thereof.

The dominant features of the design reside in the portion shown in full line.

I claim:

The ornamental design for a table lamp, substantially as shown and described.
